SPRING CUSHION FOR UPHOLSTERED FURNITURE

Albert M. Bank, Jersey City, N. J.

Application January 27, 1948, Serial No. 4,663

2 Claims. (CL 5—272)

1

This invention relates to spring cushions for upholstered furniture. It is particularly directed to a metal spring assembly, which is covered with padding and incorporated into a seat or back cushion for a sofa, chair, or like upholstered article of furniture.

An object of this invention is to provide a spring cushion of the character described, comprising top and bottom edge frames, rows of coil springs therebetween, the end convolution of each coil spring overlapping the end convolution of coil spring or springs adjacent thereto, and top and bottom wires transversely of said rows for interconnecting and clamping together the overlapping end convolutions of said springs, each wire having central integral portions projecting between a pair of overlapped convolutions and interconnected by a hook extending to one side and engaging beneath the underlapping convolution, and integral portions on opposite sides of the central hook portion, projecting between said convolutions but beyond the overlapping portions and interconnected by hooks extending in a direction opposite to the first hook and engaging beneath the underlapping convolution, and portions of the wire between said central hook and said pair of hooks, pressing down on the overlapped convolution, to clamp said convolutions together, whereby the end convolution of said springs are held against swivel movement, one relative to the other when weight is imposed on the cushion.

Another object of this invention is to provide a spring cushion of the character described, wherein the spring coils have overlapping end convolutions locked together against swivelling by locking or clamping wires which engage each pair of overlapping contacting convolutions, pressing them together, whereby said cushion will give more distributed support when weight is imposed thereon, and whereby the spring coils are locked and suspended between the locking wires.

Still another object of this invention is to provide an improved compact, strong and durable spring cushion of the character described, which shall be relatively inexpensive to manufacture, easy to assemble, comfortable in use, and yet practical and efficient to a high degree.

Other objects of this invention will in part be obvious and in part hereinafter pointed out.

The invention accordingly consists in the features of construction, combination of elements, and arrangement of parts, which will be exemplified in the construction hereinafter described,

and of which the scope of invention will be indicated in the following claims.

In the accompanying drawings, in which is shown various illustrative embodiments of this invention,

Fig. 1 is a top plan view of a spring cushion embodying the invention;

Fig. 2 is a side elevational view thereof;

Fig. 3 is an enlarged view illustrating the locking of a pair of overlapping convolutions by a locking or clamping wire;

Fig. 4 is a side elevational view of the structure of Fig. 3;

Fig. 5 is a cross-sectional view taken on line 5—5 of Fig. 3;

Fig. 6 is a cross-sectional view taken on line 6—6 of Fig. 3, and

Fig. 7 is a cross-sectional view taken on line 7—7 of Fig. 3.

20 Referring now in detail to the drawing, 10 designates a spring cushion embodying the invention. The same comprises top and bottom opposed, parallel edge frames 11, which may be made of wire. Each frame may be made of a single piece 25 of wire bent to desired rectangular shape with curved corners and with ends overlapping and clamped together by clips 12. The frames 11 are interconnected by a spring assembly 13.

Said spring assembly 13 comprises a plurality 30 of parallel, spaced, aligned rows of coil springs 14, which may be of the hour-glass shaped type, well known in the art. Thus, there are end rows 15 of springs, and intermediate rows 16 of springs. End convolutions of the coil springs are attached 35 to the end frames 11 by clips 18 and 19, as shown in the drawing.

The end convolutions of the coil springs are locked and clamped together by parallel locking or clamping wires 21. Said end convolutions 40 are overlapping, as will be described hereinafter. Since the locking constructions at the top and bottom of the cushion are similar and symmetrically disposed, only the construction of the top will be described.

45 Referring therefore only to the top of the cushion, the end convolution of the spring 14a at the left end of each row, designated by numeral 25, underlaps the end convolution 26 of the next adjacent spring 14b. Said convolution 26, however, underlaps the end convolution 27 of the next adjacent spring 14b. Said end convolution 27 underlaps the end convolution 28 of the end spring 14a in said row. Thus, each of the convolutions 26 and 27 of the intermediate 55 springs overlaps the end convolution of a spring

on one side thereof, and underlaps the end convolution of a spring at the opposite side thereof.

The locking or clamping wires 21 are parallel to one another and extend transversely of the rows 15 and 16. Thus, there is one locking wire between the adjacent springs 14a, 14b of the rows 15 and 16. Also there is a locking wire 21 between the intermediate springs 14b of the rows 15 and 16.

In Figs. 3, 4, 5, 6 and 7 there is illustrated the locking of a pair of overlapping convolution portions 25, 26, which will illustrate the construction at each overlap. The wire 21 has wire portions 40 contacting the overlapping convolution 26 at the points where it crosses the underlapping convolution 25. Extending from the inner ends of wire portions 40 are downwardly extending spaced parallel wire portions 41 which are interconnected by a hook 42 which extends to the right and engages beneath the underlapping convolution 25. It will be noted that the wire portions 41 project downwardly between the overlapped wire portions 25, 26 and the hook 42 is disposed in a vertical plane through the axes of the springs in one row. Extending downwardly from the outer ends of wire portions 40 are wire portions 43 located just beyond the crossing portions of the wires 25, 26.

Extending from wire portions 43 in a direction opposite to the direction of hook 42 are hooks 44 which engage beneath the underlapping convolution 25. Extending upwardly from the hooks 44 are wire portions 45 parallel to wire portions 43 and extending from the wire portions 45 in opposite directions are wire portions 46 aligned with the wire portions 40.

It will now be understood that the overlapping convolution 26 is pressed down at two points, to wit, the points where the overlapping convolution 26 crosses the underlapping convolution 25. Furthermore, the underlapping convolution is pressed upwardly at a center point and at two points beyond the place where the convolutions cross. With such construction, the convolutions 25, 26 are hooked and maintained in level condition.

Furthermore, the convolutions 25 and 26 cannot be pulled apart because of the wire portions 41 which project down through and between the overlapping portions. Also the convolutions 25, 26 cannot be moved toward each other because of engagement with the wire portions 43 which engage said convolutions just beyond the places where they cross so that said wire portions 43 are disposed between said convolutions and prevent said convolutions from being moved further toward each other in a direction to increase the overlap.

It will now be understood that the overlap cannot be increased or decreased due to the construction described hereinabove. Furthermore, convolutions 25 and 26 cannot be moved sideways, one relative to the other in directions parallel to wire 21, because such movement would be prevented by wire portions 43 as well as 41.

The convolutions 25 and 26 are restrained against swivelling movement, so that if a weight is imposed upon the spring assembly, the weight will be distributed throughout the cushion to get a better distribution of support for weight imposed on the cushion.

The ends of the locking or clamping wires 26 may be coiled around edge frames as at 50, or

otherwise clipped or attached thereto. The interlocking construction disclosed in Figs. 3 to 7 is the same at each place where the convolutions overlap and the same construction stated above is used at the top of the spring as at the bottom.

The hooks 42 and 44 exert lever action to restrain swivelling action between adjacent springs. The wires 21 are preferably made of spring steel, so that the hooks resiliently bias the end convolutions of the springs into level position.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to protect by Letters Patent:

- 25 1. In a spring cushion comprising opposite edge frames and springs interconnecting said edge frames, a pair of adjacent springs having end convolutions overlapping one another, means to lock said overlapped convolutions comprising a member having aligned portions contacting the overlapped convolution, portions extending downwardly from the inner ends of said aligned portions between the crossing portions of said convolutions and interconnected by a hook extending to one side and engaging beneath the underlapping convolution and portions extending downwardly from the outer ends of said aligned portions at points just beyond where said convolutions cross and hooks extending from said last mentioned downwardly extending portions in a direction opposite to the first hook and engaging said underlapping convolution at points beyond where said convolutions cross.
- 30 2. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
- 35 3. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
- 40 4. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
- 45 5. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
- 50 6. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
- 55 7. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
- 60 8. In a spring cushion, a pair of adjacent coil springs having convolutions overlapping one another, means to lock said overlapping convolutions comprising a member having aligned portions contacting one of the overlapping convolutions, portions extending between the crossing portions of said convolutions and interconnected by a hook extending to one side and engaging with the other overlapping convolution and portions extending from the outer ends of said aligned portions at points just beyond where said convolutions cross and hooks extending therefrom in a direction opposite to the first hook and engaging said other overlapping convolution at points beyond where said convolutions cross.
